CAROUSEL TOY
George H. Gisser, Cambria Heights, N.Y.
(7 Wilshire Drive, Spring Valley, N.Y.)
Filed June 17, 1960, Ser. No. 36,901
6 Claims. (Cl. 273—1)

The instant invention relates to roundabout devices and more particularly to a toy carousel or toy merry-go-round, the primary purpose of which is to provide amusement for children.

The general object of the present invention is to provide a toy carousel which can be remotely and individually operated by a plurality of children, thereby simulating the functions and excitement of the full-size carousel often considered the focal point of carnivals and amusement parks.

A more specific object of this invention is to provide an improved toy comprising a motor driven carousel, a plurality of rider carrying horses, a turntable supporting each horse and the rider thereof, and controls remote from each horse and rider adapted to motivate, either directly or indirectly, an arm of each rider with respect to a brass-ring feeding device.

Another object of the present invention is to provide an electromechanical or mechanical toy carousel embodying cooperative movable parts arranged to require the exercise of independent skill on the part of each of the carousel operators.

A further object of the invention is to provide a game for children whereby the degree of skill required by the game participants may be predeterminedly varied.

It is a still further object of the present invention to provide a miniature carousel sufficiently interesting in function as to be capable of capturing the attention of adults as well as children for extended periods of time.

These and further objects will become more readily apparent during a reading of the specification when examined in connection with the accompanying drawings, wherein:

FIGURE 1 is a sectional side elevation of the structure embodying the instant invention; and

FIGURE 2 is a schematic plan view of the toy carousel, emphasis being given to preferred circuitry adapted to remotely control horse and/or rider movement; and

FIGURE 3 is an expanded view of the brass-ring dispensing means; and

FIGURE 4 is an alternate embodiment, movement of rider and/or horse being effectuated by mechanical means.

Referring to the drawings and particularly to FIGURE 1 thereof, the toy carousel generally designated as 1 is comprised of a base member 2, a rotatable platform 5, a central rotatable support column 6 and a roof 8 providing a fanciful and aesthetic covering for the device.

Not unlike the full-size amusement park carousel, the device herewith concerned provides its users with the excitement of vicariously reaching for a brass-ring and with the satisfaction engendered by proper accuracy and timing in achieving their objective. Inasmuch as each participant is able to control the movement of his or her preselected horse and rider with respect to the brass ring, the challenge of independent responsibility and competition is fostered.

Operatively supported in a well-bearing 12 in the base 2 is said shaft or support column 6, which extends upwardly through the housing 11 but which at its lower end carries a beveled gear wheel 14. Vertical support column 6 is the driving shaft of the toy carousel. The beveled gear wheel 14 meshes with a smaller bevel pinion 16 carried by a shaft 17 of motor 18. The motor, connected to battery 20 contained in housing 11, is adapted in this

2

manner to drive support column 6 and thus rotate platform 5, fixedly secured thereto. It is to be understood that a power source external of the device may be employed; i.e., house current, if such becomes desirable.

A plurality of horse and rider statuettes spacedly positioned upon platform 5 rotate therewith, arms 56 and 58 of the riders illustrated in FIGURE 1 passing within the vicinity of the brass-ring holding device 80 during each revolution of the said rotating platform. Inasmuch as the position of each rider's arm may be remotely and continually adjusted with respect to the position of brass-rings 72, 73, etc., held within device 80, the primary object of the toy, i.e., reaching for and taking a brass-ring, may be accomplished.

To that end solenoid control-support members 38 and 40 adapted to regulate the positions of riders 52 and 54 are socketed within platform 5 depending upwardly therefrom. Riders 52 and 54 are illustrated as representative of the many types of electro-mechanical movements contemplated within the scope of this invention. Selected for purposes of illustration, however, is the embodiment of rider 52 wherein the arm 56 remains stationary with respect to the rider but where horse 48 is arranged for vertical movement. For the purpose of further elaboration is shown the embodiment of rider 54 wherein horse 50 does not move vertically but where arm 58 is arranged for movement in a vertical plane.

In order to impart vertical movement to horse and/or rider or to an arm of said rider, slidable solenoid core linkages are utilized. With reference to FIGURES 1 and 2 of the drawings, magnetic cores 42 and 44 are disclosed as being slidably received within coil windings 45 of the respective solenoid members. Vertical motion of said magnetic cores is occasioned by establishing a magnetic field about said magnetic cores, the degree of movement thereof being a function of the intensity of the magnetic field created. Hence, electrically energized solenoid coil windings 45 will attract magnetic cores 42 and 44 to positions central of their respective magnetic fields. Inasmuch as springs 46 tend to bias said magnetic cores away from the center of the magnetic field, predetermined variation of the strength of the field will overcome the constant bias of springs 46 in predictable degrees, thereby enabling control of horse and/or rider or an arm of said rider as may be desired. Rheostats 86 and 88 are observable in FIGURE 1 as individual control boxes, knobs 90 and 92 being capable of electrical resistance regulation, thereby varying the strengths of magnetic fields within said solenoids 45.

Reference to FIGURE 2 of the drawings schematically illustrates rheostats 86 and 88 and their respective circuit relationships to solenoids 45. Further reference to FIGURE 2 discloses that single power source 20 furnishes energy both to motor 18 and to solenoids 45 via parallel circuitry. Common central rail 30 receives a negative electrical charge through sliding contact with brush 36, switch 21 being provided to open and close the circuit created thereby. Switch 15 is further provided to start and stop rotation of circular platform 5.

Unlike common central rail 30 which is integral with and rotatable with platform 5, singular statuette rails 22, 24, 26 and 28 are integral with the base 2, thereby remaining stationary while platform 5 is in motion. Thus, it is seen that central rails 30, as heretofore mentioned, is negatively charged through brush 36. It is further seen that said singular rails 22, 24, 26 and 28 positively charged through fixed contacts, e.g., 23 and 25, receive charges varying in magnitude according to the setting of respective rheostats 86 and 88. The circuits are completed, brushes 32, 34, 35, and 37, and fixed contacts 23, 25, 27 and 29 closing the circuit through solenoids 45.

As an embodiment ancillary to the preferred embodiment previously disclosed, FIGURE 4 relates to a device of the character described wherein movement of the statuette is accomplished by solely mechanical means. With reference to said figure, rotatable platform 102 supports stanchion 103, the support member for horse 110 and the rider thereon. Arm 112 is adapted for motion in a vertical plane about pin 113, such movement being urged in a clockwise direction by virtue of spring and lever arrangement 114 and 116. Cord 120 attached to arm 112 is supported from above by pulley 121 and guided thereby toward and around pulley 126. Cord 120 is thereafter guided axially through vertical support column 127, said support column being journaled for rotation between bearings 134 and 136. The device illustrated in FIGURE 4 may be entirely bereft of electrical influence, rotation of support column and platform being occasioned by a spring wound motor adapted to drive beveled gears 128 and 130. Control cord 120 emerges concentrically from the lower end of support column 127 through flared bearing passage 132 to without base 109 to control-device 149. Movement of lever 142 about pivot point 144 transmits said movement to arm 112 thereby permitting control thereover. Twisting and subsequent binding of cord 129 is obviated by employment of swivel 122 positioned as shown, within support column 127. According to the latter embodiment, therefore, motion of arm 112 of the statuette illustrated can be most economically and simply effectuated. Movement of said arm can thusly be regulated through preselective movement of lever 142 as heretofore described, said movement corresponding in effect to the movement occasioned in the preferred electrical embodiment according to FIGURES 1 and 2 of the accompanying drawings.

Brass-ring holding device 80 illustrated in detail in FIGURE 3 of the drawings is shown in FIGURE 1 fixedly secured to supporting strut 70, the brass-ring dispensing end 74 of said device being cantilevered above rotating platform 5 and in the general vicinity of the statuettes passing nearby in the course of rotation of said platform 5. Pivottally mounted upon pin 76, brass-ring holding tube 71 is adapted to successively gravity-feed brass-rings toward lip retaining means 74 upon removal of the protruding ring, e.g., brass-ring 73 as shown in FIGURE 3. That is, should brass-ring 73 be taken by hand 75 of rider 52, brass-ring 72 will automatically roll through channel guide means 69 downwardly toward lip 74 and be held in position thereby in order that another rider may be controlled to attempt similar removal of ring 72. Removal of said rings is readily accomplished by lateral movement thereof through the openings provided in side walls 79 at the region adjacent the lip retaining means 74, as illustrated in FIGURE 1 of the drawings. The procedure will be repeated until the supply of brass-rings is depleted. Ballast weights 78 are positioned within brass-ring holding device 80 to counter-balance the combined weight of the brass-rings retained within guide channel 69. Pivottally balanced about pin 76, the brass-ring holding device will tend to move upwardly in increments at the ring holding side upon removal of the rings fed successively toward lip 74. Accordingly, the inclusion of the balanced ring feed mechanism in the carousel toy becomes desirable on occasions where an increase in the level of the game skill is sought. Hence, the degree of difficulty in achieving success may be predeterminatively varied through utilization or not of the balanced brass-ring holding device hereinabove described. Elimination of this feature from the toy may be accomplished by simply increasing weight 78 beyond the combined weight of the brass-rings held within the dispensing side of the device.

Having hereby illustrated certain details of construction which are particularly effective, it is to be understood that various changes may be made without departing from the spirit of the invention.

Consonant with the foregoing, what is claimed is:

1. A carousel toy comprised of a base member, a rotatable platform on said base member, means for rotating said platform, a central support column journaled for rotation with said rotatable platform, a roof, a plurality of statuettes spacedly positioned with respect to one another, said statuettes being supported by said rotatable platform and extending upwardly therefrom, brass-ring dispensing means supported by said base member and positioned adjacent to said rotatable platform, individual electrical remote control means to continually adjust the vertical position of respective statuettes with respect to said brass-ring dispensing means during rotation of said platform, said statuettes being movable into juxtaposition with respect to said ring dispensing means upon rotation of said rotatable platform and ring engaging means on each statuette.
2. A carousel toy according to claim 1 wherein said brass-ring dispensing means is comprised of an arm disposed in pivotal relationship with a support member extending upwardly from said base member, said arm being sloped downwardly with respect to said rotatable platform, a guide-channel disposed within said arm and said guide-channel being adapted to receive a plurality of brass-rings positioned therein in end to end relationship.
3. A carousel toy according to claim 2 wherein said arm of said brass-ring dispensing means is balanced about a pivot point and adapted to decrease in downward slope upon removal of a brass-ring disposed within said guide-channel.
4. A carousel toy comprised of a base member, a rotatable platform, means for rotating said platform on said base member, a central support column journaled for rotation with said rotatable platform, a roof, a plurality of statuettes spacedly positioned with respect to one another, said statuettes extending upwardly from said rotatable platform, solenoid power members adapted to move at least a portion of said statuettes, said members being disposed between each of said statuettes and said rotatable platform, control rheostats remotely positioned with respect to said solenoid power members, ring dispensing means pivotally supported adjacent said rotatable platform, said statuettes being movable into juxtaposition with respect to said ring dispensing means upon rotation of said rotatable platform and ring engaging means on each statuette.
5. A carousel toy comprised of a base member, a rotatable platform, means for rotating said platform on said base member, a central support column journaled for rotation with said rotatable platform, a roof, a plurality of statuettes spacedly positioned with respect to one another, said statuettes extending upwardly from said rotatable platform, solenoid power members adapted to move at least a portion of said statuettes, said members being disposed between each of said statuettes and said rotatable platform, said members being in slidable brush contact with respective rails positioned beneath said rotatable platform, control rheostats remotely positioned with respect to said solenoid power members and in brush contact with said respective rails, ring dispensing means pivotally supported adjacent said rotatable platform, said statuettes being movable into juxtaposition with respect to said ring dispensing means upon rotation of said rotatable platform and ring engaging means on each statuette.
6. A carousel toy comprised of a base member, a rotatable platform, means for rotating said platform on said base member, a central support column journaled for rotation with said rotatable platform, a roof, a plurality of statuettes spacedly positioned with respect to one another, said statuettes extending upwardly from said rotatable platform, individual electrical control means to remotely and variably effectuate vertical movement of respective statuettes, a ring dispensing member pivotally supported adjacent said rotatable platform, said member

being sloped in the direction of said statuettes, one end of said member having ballast weight therein, said statuettes being movable into juxtaposition with respect to said ring dispensing member upon rotation of said rotatable platform said rings being successively removable from the other end of said member upon contact of said statuettes and said rings, removal of said rings from said member effecting a change in the slope of said member and ring engaging means on each statuette.
